UNITED STATES PATENT OFFICE.

CARL L. KENNEY, OF DORMONT, AND STANLEY M. CASTERLINE, OF CRAFTON,
PENNSYLVANIA; SAID KENNEY ASSIGNOR TO SAID CASTERLINE.

METAL CROSSTIE.

Application filed July 28, 1922. Serial No. 578,149.

To all whom it may concern:

Be it known that we, CARL L. KENNEY and STANLEY M. CASTERLINE, citizens of the United States, residing at Dormont and 5 Crafton, respectively, in the county of Allegheny and State of Pennsylvania, have invented certain new and useful Improvements in Metal Crossties, of which the following is a specification.

10 This invention is for a one-piece tie for railroads, especially those used in and about mines, and relates particularly to a clamp construction for securing the rail in position on the tie.

15 A large number of one-piece ties for use in connection with mining operations have been devised, many of which have gone into practical use, while many others are commercially impractical. Some of those most 20 commonly used employ wedges of different kinds, while others utilize bolts and nuts, which must be applied and removed in laying and removing the rails, and which are frequently lost, holding up operations until 25 new ones can be found and applied, and which necessitate the miners carrying wrenches with which to effect the application and removal of nuts.

The present invention has for its primary 30 object to provide a clamp of simple construction which may be fixed in clamping relation or released in a moment's time, and which may be removably clamped by rail spikes, large spikes found around mines, or 35 small pieces of metal or wood found in and around mines.

Our invention may be readily understood by reference to the accompanying drawings, in which:

40 Fig. 1 is a longitudinal section through a portion of a steel tie, with our clamp applied thereto;

Fig. 2 is a transverse section on line A—A of Fig. 1;

45 Fig. 3 is a perspective view showing one end of the tie with a rail in place thereon; and

50 Figure 4 is a view similar to Fig. 1, showing a slightly heavier rail in position on the tie.

In the drawings, 5 designates a metal cross tie of any suitable shape. As shown, however, it is preferably channel-shaped in cross section, with the flanges turned downward. In the flat part of the tie, near the

end thereof, is an opening 6, this opening being so near the end that only a narrow strip or bridge of metal 7 is provided at the end of the tie. While only one end of the tie is shown, it will be understood that both ends are made alike.

Spaced back from the end of the tie a sufficient distance and riveted thereto, is a cleat 8, under which the inner flange *a* of the rail, designated A, extends.

65 A metal strap 9 has a reduced end which is bent around the integral bridge 7 to form an eye 10 on the end of the strap, by means of which the strap is hingedly secured to the tie. This strap, when swung inwardly, is 70 adapted to extend over the outer flange *a'* of the rail. So much of the construction is old in the art, and it has heretofore been the practice to secure this strap in clamping position by means of a bolt.

75 According to the present invention, the strap is preferably bent at 11 to form a resilient bow. A longitudinal slot 12 is also formed in the strap. A stud 13 is passed through the tie in juxtaposition to the slot 70 in the strap, and the lower end of the stud is riveted over to secure the stud in position. The upper end 13^a of the stud is enlarged 80 and has a slot or eye 14 therein, which slot preferably extends transversely relatively to the strap.

85 When the strap is swung over to clamping position, the upper end of the stud projects through slot 12 in the strap. A wedge member, such as an ordinary rail spike 15, is 90 then driven through slot 14 in the upper end of the stud, forcing the strap down into rail engaging position and holding it there. The bow in the strap will enable the strap to yield sufficiently to allow the spike to be 95 driven well through the slot.

As spikes are generally found in and about mines, the clamping means is ideal for use in such places. If a rail spike cannot be found immediately, large nails, scraps of 100 iron or pieces of wood may be driven through the slot or eye 14 in the stud. The strap will be sufficiently resilient to clamp the rail and the spike or other wedge will be clamped against accidental displacement by 105 the upward spring of the metal. Such wedge can be easily driven out, however, when it is desired to remove the rail.

In Fig. 1, the clamp is shown applied to a small sized rail. In Fig. 4, the rail A' is 110

heavier. Consequently, the web of the rail is disposed a slight distance nearer the outer end of the tie. When the strap is swung inwardly to clamping position, it is of such length that its free end will hit the web of the rail. By forcing the strap down, it may be sprung into position and will tightly hold the rail in place.

From the foregoing, it may be seen that 10 the clamp is effective with rails of different sizes, so that the tie can be made in a standard size to receive varying weights of rails. The clamping means is highly efficient, and the simple way in which it can be locked in 15 clamping position by driving in a cross key or wedge is far superior to the constructions which have heretofore been used.

Various detailed changes may be made in the invention different from the construction 20 shown and described, but such changes are within the contemplation of our invention and within the scope of the appended claims.

We claim as our invention:

1. A rail tie comprising a cross tie member, means on said tie member for engaging one side of a rail, a strap for engagement with the other side of the rail hingedly secured to said tie and movable into and out of rail engaging position, a projecting member on said tie, said strap having an opening therein through which said projecting member extends when the strap is in rail engaging position, and a cross member slidably engaging the projecting member and adapted to extend over said strap when said strap is in rail engaging position, for locking the strap in such position.

2. A rail tie comprising a cross tie member, means on said tie member for engaging one side of a rail, a strap for engagement with the other side of the rail hingedly secured to said tie and movable into and out of rail engaging position, a projecting member on said tie, said strap having an opening therein through which said projecting member extends when the strap is in rail engaging position, and a removable key slidably engaging the projecting member and adapted to extend over said strap when said strap is in rail engaging position, for locking the strap in such position.

3. A rail tie comprising a metallic cross tie member, a rail engaging cleat on said tie member, a rail engaging strap hingedly secured to the tie and capable of being 55 swung into and out of rail engaging posi-

tion, a projecting means on said tie, said strap having an opening therein through which the projecting means on said tie extends when the strap is in rail engaging position, said projecting member having an opening therethrough, and a cross-key removably inserted in said opening for engaging said strap when it is in rail engaging position, for locking the strap in such position.

4. A rail tie comprising a main cross tie member, a rail engaging cleat thereon, a strap having one end hingedly connected with said tie in such manner that the other end is movable through an arc into and out of rail engaging position, and cooperating means on the tie and strap for locking said strap in rail engaging position, including a transversely slidable key having cooperative engagement with the strap between the ends thereof and the means on the cross tie.

5. A rail tie comprising a main cross tie member, means thereon for engaging one side of a rail flange, means for engaging the other flange comprising a strap hingedly connected to the tie and movable into and out of rail engaging position, said strap having a slot therein, a stud member secured to said tie and having an enlarged upper end adapted to project through the slot in said strap when the strap is in rail engaging position, and transversely extending means on the enlarged upper end of said stud for locking the strap in rail engaging position.

6. A rail tie comprising a main cross tie member, means thereon for engaging one side of a rail, means for engaging the other side of the rail including a strap hingedly connected with the tie and movable into and out of rail engaging position, said strap being of such a shape as to be somewhat resilient when in engagement with a rail, a projecting means on said tie adapted to extend above the strap when the strap is in rail engaging position, and a key slidably engaging the upper part of said projecting member for locking said strap in rail engaging position, and holding said strap under compression whereby the clamping action thereof is increased and said key is frictionally held against accidental displacement.

In testimony whereof we affix our signatures.

CARL L. KENNEY.
STANLEY M. CASTERLINE.
